UNITED STATES PATENT OFFICE.

CHARLES V. WARREN, OF CAMBRIDGE, MASSACHUSETTS, ASSIGNOR TO FREDERICK L. EMERY, OF LEXINGTON, MASSACHUSETTS.

LUBRICATOR FOR ELEVATOR GUIDE-RAILS.

1,171,157.

Specification of Letters Patent.

Patented Feb. 8, 1916.

Application filed January 4, 1912. Serial No. 669,431.

To all whom it may concern:

Be it known that I, CHARLES V. WARREN, a citizen of the United States, and a resident of Cambridge, in the county of Middlesex 5 and State of Massachusetts, have invented an Improvement in Lubricators for Elevator Guide-Rails, of which the following description, in connection with the accompanying drawings, is a specification, like 10 characters on the drawings representing like parts.

My invention relates to lubricators and more particularly to devices for lubricating elevator or similar guides, and has in view 15 such a device as will feed the oil economically yet keeping the guide sufficiently and substantially uniformly lubricated.

My invention will be best understood by reference to the following description when 20 taken in connection with the accompanying illustration of one specific embodiment thereof, while its scope will be more particularly pointed out in the appended claims.

25 In the drawings: Figure 1 is an elevation of an elevator guide rail lubricator embodying my invention as applied to an elevator car and its guide rail. Fig. 2 is a central vertical sectional view of the lubricator at 30 an enlarged scale showing the support partly broken away. Fig. 3 is a detailed sectional view taken on line 3—3 of Fig. 2 looking toward the left.

Referring to the drawings and to the embodiment of my invention therein shown: 35 1 represents a portion of an elevator car of any usual construction having a shoe 2 arranged to slide vertically upon a guide rail 3 in a manner well known to those skilled 40 in the art. A lubricant reservoir or can 4 is mounted on the elevator car 1, herein upon a fixed support 5 secured to the car in any suitable manner, in the present instance being secured to the shoe 2. The lubricator 45 reservoir or can 4 is mounted upon the support 5 in any suitable manner as by providing said reservoir with a laterally extending tubular nose 6 fixed with respect to the reservoir and preferably extending a 50 short distance thereinto. Herein the nose or guide 6 is clamped to the support 5 by means of a yoke 7, there being provided bolts 8, 8 passing through the yoke and support above and below the nose and serving 55 to draw the yoke toward the support, thus

firmly gripping the nose and serving to support the reservoir in fixed position. The nose 6 constitutes a guide for a wick tube 9 which is mounted to slide longitudinally within the said nose. Located within the 60 reservoir 4 is a suitable wick 10 preferably of cotton, which I have found feeds the oil very satisfactorily by capillary action. This wick extends upwardly within the reservoir and thence laterally through the wick 65 tube 9 into engagement with the guide rail 3 and is constantly yieldingly urged against said guide rail by suitable resilient means, herein a spring 11. In the form herein shown this spring is of the helical type and encircles the wick tube 9 where it projects beyond the nose 6. One end of this spring bears against the outer end of the nose and at the other against a suitable abutment on the wick tube, herein consisting of a collar 75 or boss 12 secured to the outer end of the wick tube in any suitable manner as by soldering.

Suitable means are provided for limiting the longitudinal sliding movement of the 80 wick tube, herein consisting of a pin or other projection 13 secured to the wick tube and arranged to play to and fro in a slot 14 provided in the nose 6. When the lubricator is mounted upon the elevator car the projection 13 will be placed substantially in a central position in the slot 14 so as to be capable of moving in either direction. It will be evident that the spring will serve to maintain the outer end of the wick in contact 85 with the guide rail and will compensate for irregularities in the guide rail. Some guide rails are more or less irregular or out of true and it will accordingly be evident that suitable provision must be made for maintaining the wick in contact with the rail regardless of any such irregularities that may 90 exist.

In order that the wick may be prevented 95 from receding into the wick-tube under the influence of the pressure of the spring, I provide suitable means to prevent such inward yielding, herein consisting of one or more stops 15, herein two, formed by punching the walls of the tube inwardly to form two laterally yielding tongues having their free ends extending toward the outer end of the tube. These stops serve to effectually prevent the wick from being forced back into its tube but permit it to be withdrawn 100 105 110

from the latter as the end of the wick wears away.

In operation the lubricant reservoir will be supplied with suitable oil through a suitable opening 16 herein shown at the top of the reservoir and having a suitable filling cap 17.

While I have herein shown and described one form of my invention for illustrative purposes and have disclosed and discussed in detail the construction and arrangement incidental to one specific application thereof, it is to be understood that the invention is limited neither to the mere details or relative arrangement of parts, nor to its specific application herein shown, but that extensive deviations from the illustrated form or embodiment of the invention may be made without departing from the principles thereof.

Having thus described my invention, what I claim is:

1. The combination of an oil can having a nose, a cylinder adapted to reciprocate within said nose, said cylinder having an enlarged end, a spiral spring arranged between the end of the nose and the enlarged end of the cylinder.

2. In a lubricator for elevators, in combination, a nose, on one side thereof, a member slidable within said nose and having a boss on the end thereof, and resilient means contacting the nose and the boss and tending to hold the member outwardly.

3. In a lubricator for elevator guides, a nose having a slot therein, a member extending beyond said nose and having a projection thereon slidable within said slot, a boss upon said member, and a spring mounted upon said member between the end of the nose and the boss tending to keep the projection in one end of the slot.

4. In a lubricator for elevator guides, a nose projecting through one side of the lubricator and having a slot therein, a cylindrical member within said nose extending beyond the same and having a projection engaging said slot and also having a boss upon the outer end thereof, a spiral spring mounted upon said cylindrical member and located between the nose of the lubricator and the boss of the said member, and a wick adjustably secured in said member.

5. In a lubricator for elevator guides, a lubricant cup adapted to be secured to the elevator, an extensible member secured to the cup and having a wick therein one end of which extends into the cup and means for causing the other end of the wick to engage the elevator guide rail regardless of the distance between the lubricant cup and the said rail.

6. In a lubricator for elevator guides, a lubricant cup adapted to be secured to the elevator a nose on said cup, and a recipro-

cating member within said nose to compensate for the varying distance between the cup and the guide.

7. In a lubricator for elevator guides, a nose having a slot therein, a member within said nose having a projection engaging the slot in the nose, and a wick adjustably secured in said member.

8. A lubricator for elevator guides having, in combination, a lubricant reservoir having a nose fixed with respect thereto and extending laterally therefrom, a wick tube mounted to slide longitudinally in said nose, a wick extending upwardly within said reservoir and thence laterally through said wick tube, and resilient means urging said wick and tube laterally outward from said reservoir.

9. A lubricator for elevator guides having, in combination, a lubricant reservoir having a nose fixed with respect thereto and extending laterally therefrom, a wick tube mounted to slide longitudinally in said nose, a wick extending upwardly within said reservoir and thence laterally through said wick tube, resilient means urging said wick and tube laterally outward from said reservoir, and means limiting such outward movement of said wick and tube.

10. A lubricator for elevator guides having, in combination, a lubricant reservoir having a lateral opening, a wick extending upwardly within said reservoir and thence laterally through said opening, and resilient means urging said wick laterally outward from said reservoir.

11. A lubricator for elevator guides having, in combination, a lubricant reservoir having a lateral opening, a wick extending upwardly within said reservoir and thence laterally through said opening, resilient means urging said wick laterally outward from said reservoir, and means limiting such outward movement of said wick.

12. A lubricator for elevator guides having, in combination, a lubricant reservoir, a wick tube extending laterally therefrom, a guide in which said wick tube is mounted to slide longitudinally, a wick extending upwardly within said reservoir and thence laterally through said wick tube, and means acting to yieldingly urge said wick and tube laterally outward from said reservoir.

13. A lubricator for elevator guides having, in combination, a lubricant reservoir, a wick tube extending therefrom, a wick extending from said reservoir through said tube, means acting to yieldingly urge said wick and tube outwardly with respect to said reservoir, and means to prevent said wick from receding into said tube.

14. A lubricator for elevator guides having, in combination, a lubricant reservoir, a wick tube extending therefrom, a wick extending from said reservoir through said

5 tube, means acting to yieldingly urge said wick and tube outwardly with respect to said reservoir, and means acting automatically to prevent said wick from receding into said tube while permitting it to be withdrawn therefrom.

10 15. A lubricator for elevator guides having, in combination, a lubricant reservoir, a wick tube extending therefrom, a wick extending from said reservoir through said tube, means acting to yieldingly urge said wick and tube outwardly with respect to said reservoir, and means comprising a laterally yielding stop to prevent said wick 15 from receding into said tube while permitting it to be withdrawn therefrom.

20 16. A lubricator for elevator guides having, in combination a lubricant reservoir, a wick tube extending therefrom, a wick extending from said reservoir through said tube, means acting to yieldingly urge said wick and tube outwardly with respect to said reservoir, and means comprising a laterally yielding tongue projecting inwardly

25 and forwardly within said tube and having its free end engaging said wick to prevent said wick from receding into said tube while permitting it to be withdrawn therefrom.

17. The combination with an elevator guide rail, of a lubricant reservoir, a wick tube, a wick extending from said reservoir through said tube, means yieldingly to urge said wick and tube toward said guide rail, and means to secure said wick to said tube.

30 18. In a lubricator, the combination of a reservoir, a wick tube, a wick extending upward and laterally from said reservoir and through said wick tube, means to secure said wick to said tube, and means to cause said tube to press said wick laterally against the 35 surface to be lubricated.

40 In testimony whereof, I have signed my name to this specification, in the presence of two subscribing witnesses.

CHARLES V. WARREN.
